FOUNTAIN TOOTHBRUSH

Horatio R. De Luca, Bridgeport, Conn.

Application December 18, 1931, Serial No. 581,784

5 Claims. (Cl. 15—135)

This invention relates to new and useful improvements in fountain toothbrushes and has particular relation to that type of fountain toothbrush adapted to be carried on the person.

5 An object of the invention is to provide a fountain toothbrush of the character stated and which when closed, as for carrying in a pocket, resembles a fountain pen and includes a pocket clip for securing it in a pocket and against loss.

10 It may thus be easily carried for use at any time.

Another object is to provide a toothbrush as described and which includes a removable cap normally disposed to cover the fountain head of the brush and a hollow body adapted to receive 15 a tube of tooth paste with the neck of the tube threaded into the hollow brush head, means being provided for manual operation to crush or collapse the tube in a manner to feed the paste to the brush as required, and said hollow body functioning as a handle while the brush is in use.

20 A further object is to provide a toothbrush having the characteristics stated and which is adapted to receive a complete or full tube of tooth paste as purchased from a store, the tube being in the 25 nature of a refill, and the paste being fed directly from the tube into the head of the brush.

Other objects and advantages will become apparent from a consideration of the following detailed description taken in connection with the 30 accompanying drawing wherein a satisfactory embodiment of the invention is shown. However, since the drawing and description are for the purpose of disclosure only, it will be understood that the invention is not limited to the details shown and described, but includes all such 35 variations and modifications as fall within the spirit of the invention and the scope of the appended claims to which claims reference should be had for a definition of the invention.

40 In the drawing:

Fig. 1 is a side elevational view of a complete fountain toothbrush in accordance with the present invention, the brush being shown closed;

Fig. 2 is a longitudinal sectional view through 45 the brush of Fig. 1;

Fig. 3 is a transverse sectional view on an enlarged scale, taken substantially along the line 3—3 of Fig. 2;

Fig. 4 is a detailed sectional view on an enlarged 50 scale, the view being taken substantially along the line 4—4 of Fig. 2;

Fig. 5 is a transverse sectional view taken substantially along the line 5—5 of Fig. 2;

Fig. 6 is a plan view of a blank adapted to be 55 applied to the end of a tube of toothpaste and be

used as a key for winding up the tube to expel the paste therefrom; and

Fig. 7 is a view suggesting the manner of applying the winding element or key of Fig. 6.

Referring in detail to the drawing, the improved brush as herein disclosed includes a substantially cylindrical body member 10 closed at one end as by a removable cap 11 and having its other end portion drawn inwardly as at 12 and then shaped to provide a reduced neck portion 13 internally screw threaded as shown. Toward its inner end the body member 10 is externally screw threaded as at 14 whereby the closed end cap member 15 may be threaded into place on the body member.

At 16 is generally indicated a brush head including a stem 17 and a back 18 carrying bristles 19. The stem and back of the brush head are formed with a passage 20 through them, the said passage opening to the bristles 19 at one or more points as at 21. The free end portion of the stem 17 of the brush head is externally screw threaded as at 22 whereby the brush head may be threaded into the neck portion 13 of the body member 10 and thereby adapt the body member to function 70 as a handle when the brush is in use.

At 23 is shown a tube 26 of tooth paste arranged in the body 10. The tube 26 is inserted into the body through that end of the body normally closed by the removable cap 11 and after the brush head has been disconnected or partially disconnected from the body. With the tube disposed within the body in position 75 to have its neck portion 25 entering the neck portion 13 of the body the brush head is threaded into place in the neck of the body. By this same action the internal threads 24 on the stem of the brush head engage the threads on the neck 80 25 of the tube with the result that all of the parts are so connected that the body forms a handle for the brush head and paste expelled from the tube will enter directly into the brush head.

Means are provided whereby the tube will be 100 held against turning movement in the body while the brush head is being threaded into place and this means also is adapted for operation to collapse or crush the tube 26 in a manner to expel the paste therefrom and into the brush head. 105 This means may be termed a key or winding device and as shown in Figs. 2, 3 and 4 it is generally indicated by the reference character 27 and includes a stem 28 having a small disc 29 formed with or secured to one of its ends.

The winding device or key 27 is preferably permanently attached to the tube 26 as at the factory whereby the tube when purchased will be equipped with this device. In applying the key 5 or winding device 27 its stem portion is disposed against the end portions 30 of the tube and these end portions are then carried about the stem as at 31 after which a cap 32 is applied. The stem portion 28 may, if desired, be provided with spaced 10 openings and the cap 32 may in one of its side wall portions, as for example that designated 33, be provided with perforations while in its wall portion 34 it may carry slight lugs or projections. With such an arrangement the cap would be 15 pressed in place and the material of the end portions of the tube would be pressed into the spaced openings in the key whereby the key will be securely and permanently attached to the tube.

At its end opposite that at which it carries the 20 small disc 29 the stem 28 of the winding device is provided with a finger piece or button 35 which may be roughened or knurled on its periphery as shown. To accommodate this small disc like portion 29 of the winding device the body 10 is pressed 25 to form, or bent to form, an outwardly off-set portion 36 having a T-shaped slot 37 therein, the portion and slot extending longitudinally of the body. Diametrically opposite this portion 36 the body is longitudinally slotted as at 38 and from 30 Figs. 2 and 3 it will be apparent that while the disc 29 is received in the slot 37 the opposite portion of the stem 28 extends through the slot 38 in the body whereby the finger piece 35 is disposed at the outer side of the body in position for easy 35 manipulation.

The guideway 37 and the slot 38 extend through the upper or outer end of the body and when a new tube 26 is to be introduced into the body the cap 11 is removed and the tube slipped into the 40 open end of the body with the disc 29 disposed in the guideway 37 and the stem 28 arranged in the slot 38. It will therefore be seen that a new tube is easily introduced into the body and that the tube will be held against turning movement 45 on its longitudinal axis during the time the brush head 16 is being threaded to the tube and body.

It will be noted that as clearly shown in Fig. 2 the tube 26 tapers toward its neck portion 25, this 50 particular structure being provided in order to prevent the tube from binding in the body as the tube is wound about the key or winding device 27. The operation of expelling the paste from the tube and into the brush head involves the turning of the finger piece 35 so as to rotate the stem 28 and 55 wind up the tube. The winding device is guided downwardly and held against lateral movement since its portions are disposed in the guideway 37 and slot 38 and the diameter of the portion about the winding device will increase but will not reach the point where it binds in the body owing to 60 the fact that the tube is tapered.

When a tube of paste has been used up it is but necessary to unscrew the brush head outwardly in a manner to disengage the threads on the stem of the brush from those on the neck of the tube after which closure or cap 11 may be removed and the exhausted tube slipped out of the body. A new tube may be introduced as above described and as above suggested it is preferred 65 that the tubes be sold in the nature of refills in that they be equipped with a winding device 27 at the factory.

Cap 15 is provided to cover the brush head when the brush is not in use and it will be apparent 70 that this cap may be easily threaded to the body

and easily removed from the body. Preferably, the cap is provided with ventilating slots or openings 39 so the bristles can dry out, these openings being provided toward the outer or closed end portion of the cap and adjacent that portion of the cap disposed about the bristles 19 of the brush. To prevent clogging of the paste in the opening 40 in the neck 25 of the tube this opening 40 is preferably made straight as shown. Were the opening tapered there might be a tendency for the paste to clog in the opening and become hardened therein. If desired a pocket clip 41 of any desired construction may be attached to the body.

In the use of the device the tube 26 is fully enclosed by the body 10 and since the body is rigid, being formed of metal or a relatively hard moulded compound the tube will not be unintentionally squeezed in a manner to expel the paste therefrom. It will be understood that the device may be made up of any desired material as metal, a 80 moulded phenolic condensation product or the like, and so proportioned and colored as to have a 85 pleasing appearance and to closely resemble the 90 ordinary style of fountain pen.

Figs. 6 and 7 show a slightly modified construction of winding device which may if desired be applied by the user to a tube of paste. This device generally indicated at 42 includes a blank or plate like body portion 43 stamped from sheet metal and which at one end carries a pair of fingers or extensions 44 enlarged on their outer ends as at 45. Extending from the other end of the body portion 43 is a pair of fingers or extensions 46 carrying a strip 47. Preferably these parts are all integral being blanked from a single sheet of metal.

The winding device 42 is applied to the end of a tube of paste as suggested in Fig. 7 and to this end the device is bent to substantially V-shaped and disposed on the tube with its folded end seated in the V. The key is then bent or clamped to have its opposite edge portions disposed against the sides of the closed end of the tube to seal it in the manner of the usual cap, and in order that the parts may be tightly and securely engaged the 100 body or plate 43 may be perforated as at 48 at one side of its longitudinal center line and may have portions depressed to provide lugs or projections 49 at the opposite side of its longitudinal center line. When the device is applied to a tube of 105 paste as above suggested and tightly pressed into place portions of the material of the tube will be pressed into the perforations 48 by the lugs or projections 49 and the device securely applied.

In this modified arrangement the strip or sealing cap 29 will provide the hand piece or operating portion corresponding with the wheel 35 of the previously described embodiment and the lugs or enlargements 45 will operate in the guideway 37 as in the case of the disc 49 of the form shown 115 in Figs. 1 to 4. A tube equipped with the winding device 42 of Figs. 6 and 7 is adapted to be used in connection with the body 10 and brush head 16 as in the case of the winding device or key first 120 described and further description is therefore 125 unnecessary.

The cap 11 preferably has a similarly shaped rib 50 on one side to receive and cover the end of the guide 36, and the cap and body may have complementary lugs and recesses 51 to engage to 130 retain the cap 11 on the body against accidental displacement.

Having thus set forth the nature of my invention, what I claim is:

1. A toothbrush comprising a body member, 135

said member having a reduced internally threaded open ended neck at one end, a hollow brush head threaded into said neck whereby the body member forms a handle, a tube of toothpaste in 5 the body and having its neck threaded into said hollow brush head, a key secured to the end of the toothpaste tube and adapted to be rotated to wind the tube about the key for collapsing the tube to feed the toothpaste into the brush head, and said 10 toothpaste tube tapered toward its neck whereby it will not bind in the member as it is wound about the key.

2. A toothbrush comprising a body member open at one end, a hollow brush head at said end 15 of the body whereby the body forms a handle, a tube of toothpaste in the body and arranged to discharge into the brush head, said body having a longitudinally extending slot in one wall, said body having a T-shaped guideway in its opposite wall, a key secured to the end of the toothpaste tube and having a headed portion in said guideway and a portion extending through said slot, and said key adapted to be rotated in a manner to wind the tube about the key and feed the toothpaste into the brush head.

3. A toothbrush comprising a body member open at its opposite ends, a hollow brush head at one end of the body whereby the body forms a handle, a tube of toothpaste in the body and arranged to discharge into the brush head, said body having a longitudinally extending slot in one wall, said body having a guideway in its opposite wall, a key secured to the end of the toothpaste tube and having a portion in said guideway and a portion extending through said slot, said slot and guideway opening through the end 30 of the tube opposite that at which the brush head is disposed whereby a tube equipped with the key may be inserted into the body, and said key adapted to be rotated in a manner to wind the tube about the key and feed the toothpaste into the brush head.

4. A toothbrush comprising a body member open at its opposite ends, a hollow brush head at one end of the body whereby the body forms 35

a handle, a tube of toothpaste in the body and arranged to discharge into the brush head, said body having a longitudinally extending slot in one wall, said body having a guideway in its opposite wall, a key secured to the end of the toothpaste tube and having a portion in said guideway and a portion extending through said slot, said slot and guideway opening through the end 40 of the tube opposite that at which the brush head is disposed whereby a tube equipped with the key may be inserted into the body, and said key adapted to be rotated in a manner to wind the tube about the key and feed the toothpaste into the brush head.

5. A toothbrush comprising a body member open at its opposite ends, a hollow brush head at one end of the body whereby the body forms a handle, a tube of toothpaste in the body and arranged to discharge into the brush head, said body having a longitudinally extending slot in one wall, said body having a guideway in its opposite wall, a key secured to the end of the toothpaste tube and having a portion in said guideway and a portion extending through said slot, said slot and guideway opening through the end 45 of the tube opposite that at which the brush head is disposed whereby a tube equipped with the key may be inserted into the body, and said key adapted to be rotated in a manner to wind the tube about the key and feed the toothpaste into the brush head.
